UNITED STATES PATENT OFFICE.

MERRILL WATSON, OF EAST ORANGE, NEW JERSEY, AND HERBERT J. SMITH, OF NEW HAVEN, CONNECTICUT; JOHN H. WATSON, ADMINISTRATOR OF SAID MERRILL WATSON, DECEASED, ASSIGNEES TO AMERICAN FIBRE COOPERAGE COMPANY INC., OF DOVER, DELAWARE, A CORPORATION OF DELAWARE.

PAPER-BOARD BARREL AND METHOD OF MAKING SAME.

Application filed August 22, 1922. Serial No. 583,553.

To all whom it may concern:

Be it known that we, MERRILL WATSON and HERBERT J. SMITH, citizens of the United States, and residents, respectively, 5 of East Orange, in the county of Essex and State of New Jersey, and New Haven, in the county of New Haven and State of Connecticut, have invented certain new and useful Improvements in Paper-Board Barrels 10 and Methods of Making Same; and we do hereby declare the following to be a full, clear, and exact description of the invention, such as will enable others skilled in the art to which it appertains to make and use 15 the same.

The invention relates to barrels formed of paperboard or like material and the method of making the same, and comprises certain improvements upon the barrel dis- 20 closed in application Serial No. 523,306.

The barrel of the aforesaid application is made up of a series of paperboard staves which are formed with transversely ar- 25 ranged bends adjacent their opposite ends providing shoulders at the inner side of the staves for the support of the barrel heads and grooves at the outer side of the staves to receive a fastening hoop for holding the parts together, the hoop being ar- 30 ranged just below the plane of the heads. With such construction and arrangement, however, the parts are not as closely and firmly united as it is desirable to have them for some uses to which the barrels are put, 35 and for such reason it has been one of the main objects of our present invention to improve the construction of paperboard barrels of the type in question in a manner whereby a tighter and stronger barrel will 40 be produced than heretofore and one presenting a neat and attractive finished appearance.

Other objects and advantages of the in- 45 vention will be referred to in the detailed description which follows.

Referring now to the accompanying drawings illustrating the invention,

Figure 1 is a perspective view of a suit- 50 able paperboard blank for forming a stave; Fig. 2 is a plan view of a complete stave looking toward the inside;

Fig. 3 is a plan view of the stave from the outside;

Fig. 4 is a perspective view of a complete barrel;

Fig. 5 is an enlarged end view of the stave shown in Figs. 2 and 3.

Fig. 6 is an enlarged detail, partly in section, showing the joint or connection between one of the heads, a stave and a fas- 60 tening hoop;

Fig. 7 is a detail of one of the barrel heads;

Fig. 8 is an enlarged top plan of two ends of one of the fastening hoops joined or 65 clinched by a sealing device;

Fig. 9 is a view of the same from the op- 70 posite or under side; and,

Fig. 10 is a section on the line 10—10 of Fig. 8.

In these drawings, 1 indicates the paper- 75 board blank for forming a single stave, the same preferably comprising a series of plies of rectangular sheets of paperboard, united by a suitable adhesive such, for example, as silicate of soda, which will have the effect of first softening the blank to render the same more or less plastic and pliable, and subsequently to set or harden and retain the blank in the ultimate form 80 imparted thereto by the succeeding opera- tions.

While the blank is still plastic or soft, due to the action of the adhesive, it is placed in a suitable press, which reduces 85 the blank to its final stave-like form, namely, with the proper bilge produced by im- parting a longitudinal curvature from end to end and a transverse curvature from side to side as illustrated. During the pressing 90 operation there is formed in the blank a median longitudinal groove 2, which increases in depth and width from the center of the blank toward each end, said groove comprising a relatively narrow shallow 95 middle portion and outwardly flaring deep- ening end sections 3 which have the ef- fect of producing the necessary taper of the stave from the middle portion to- 100 wards the ends. In addition to these grooves 2, there are also formed during the pressing operation transverse bends 3 ad- jacent the respective ends of the stave, which bends provide grooves 4 at the inner side of the stave and corresponding ribs 5 at the outer side of the stave, the said

grooves 4 forming seats to receive and support the barrel heads 6. After removal from the press, the staves are then preferably beveled at their longitudinal edges to assure a close joint between the same at such point.

In making up a barrel from these staves, the required number of staves are assembled in barrel formation and the heads 6 seated in the grooves 4, after which metallic fastening hoops, 7 and 8, are drawn about the staves under sufficient tension to bring the several parts of the barrel into close contact at their adjacent edges and then, while still under tension, each are fastened together at their ends.

Any desired number of these fastening hoops may be employed according to the size of the barrels or the uses to which they are to be put, but in any event the end hoops 7 will be placed in a position directly opposite the grooves 4 in which the barrel heads are seated, as shown in Fig. 6, in order to positively lock the heads in said grooves by preventing any outward movement of the staves at such point. As a means to hold the end fastening hoops in their locking position opposite the head retaining grooves 4, said hoops are bent transversely to conform to the ribs 5, as shown, whereby they will be positively locked against displacement in a direction lengthwise of the barrel.

The ends of the several hoops may be secured together in any suitable way. In the present instance, the ends of the hoop are brought to a position overlapping each other and then locked together by a so-called sealing device, which comprises a plate 10 formed to embrace the lateral edges of the overlapping hoop ends and having cut-outs 11, providing oppositely-located end walls 12, 12, between which bent sections 13 of the overlapping hoops extend for engagement therewith, the engagement of the hoop sections 13 with the end walls 12, 12, of the sealing device serving to positively lock the ends of the hoops together.

The operation of securing the ends of the hoops by the sealing device in the manner shown and described, that is, drawing the ends of the hoops together under tension and then securing them while under tension by bending or deflecting the sections 13 of the overlapping hoop ends downwardly between the oppositely-located end walls 12, 12, of the plate 10, may be effected by any suitable means, but is preferably accomplished by a tool especially, adapted for the work but forming no part of our present invention. In order that this sealing operation may be effected in a manner to assure the tension of the hoops being maintained following said operation, the latter preferably takes place opposite one of the longitudinal grooves or depressions 2 which

provides space in which to manipulate the sealing tool without drawing the adjacent portions of the hoops outwardly to any appreciable extent from the face of the barrel, and subsequent to the sealing operation said groove receives the underside of the sealing devices so that the hoops may lie close to the face of the barrel throughout their length. 70

By sealing the fastening hoops in the manner described, the barrel or container is thereby sealed and cannot have its contents removed or tampered with without destruction of the entire package, as the hoops cannot be removed whole without destroying the seals and these cannot be replaced without the special tool required. 75 80

What we claim is:

1. A barrel comprising a plurality of adjoining staves, each formed from a blank of paperboard and having a depression in its outer wall and a transverse bend adjacent each end, each of said bends providing a groove at the inner side of the barrel and a raised rib at the outer side thereof, heads seated in said grooves in the adjoining staves, metallic fastening hoops surrounding the barrel to maintain the staves and heads in fixed relation, said hoops overlying the ribs in position opposite the heads, and fastening devices securing the ends of the hoops located in position opposite one or more of the said depressions in the staves. 95

2. A barrel comprising a plurality of adjoining staves, each formed from a blank of paperboard and having a longitudinal groove in its outer wall and a transverse bend adjacent each end, each of said bends providing a groove at the inner side of the barrel and a raised rib at the outer side thereof, heads seated in said grooves in the adjoining staves, metallic fastening hoops surrounding the barrel to maintain the staves and heads in fixed relation, said hoops overlying the ribs and conforming in cross-section thereto whereby they will be held in position opposite the heads and against displacement lengthwise of the barrel, and fastening devices securing the ends of the hoops located in position opposite one or more of the said longitudinal grooves in the staves. 100 105 110

3. The method of forming barrels of staves of paperboard or like material having depressions in their outer walls, which comprises assembling the staves in barrel formation, placing heads in position, and securing the staves together by placing hoops about the same and clamping the ends of the hoops at positions opposite the depressions in the staves. 120 125

4. The method of forming barrels of staves of paperboard or like material having depressions in their outer walls, which comprises assembling the staves in barrel formation, placing heads in position, and secur- 130

ing the staves together by drawing hoops about the same and applying fastening devices to the ends of the hoops at positions opposite said depressions in the staves while 5 the hoops are held under tension.

5. The method of forming barrels of staves of paperboard or like material having longitudinal grooves in their outer walls, which comprises assembling the staves in 10 barrel formation, placing heads in position,

and securing the staves together by drawing hoops about the same and applying fastening devices to the ends of the hoops at positions opposite said grooves in the staves while the hoops are held under tension. 15

In testimony whereof we affix our signature.

MERRILL WATSON.
HERBERT J. SMITH.
